(57) **CLAIM**

The ornamental design for a beaded cross, as shown.

DESCRIPTION

FIG. 1 is a perspective view looking down at the right front side of the beaded cross, showing the new design;

FIG. 2 is a front view;

FIG. 3 is a rear view;

FIG. 4 is a top view;

FIG. 5 is a bottom view;

FIG. 6 is a left side view; and,

FIG. 7 is a right side view.

The broken line showing of coloring or shading of the beads is for illustrative purposes only and forms no part of the claimed design.
